UNITED STATES PATENT OFFICE.

JESSE A. CRANDALL, OF BROOKLYN, NEW YORK.

DESIGN FOR A TOY RATTLE.

SPECIFICATION forming part of Design No. 21,765, dated August 9, 1892.

Application filed June 28, 1892. Serial No. 438,329. Term of patent 7 years.

To all whom it may concern:

Be it known that I, JESSE A. CRANDALL, a citizen of the United States, residing at Brooklyn, in the county of Kings, State of New York, 5 have invented certain new and useful Improvements in a Design for a Rattle, of which the following is a specification, reference being had therein to the accompanying drawing.

The drawing represents a view of the design.

The leading feature of the design consists of the configuration and ornamentation of the upper terminal.

A is a rattle having the end terminating in

the representation of a head B. A shield-like portion C is shown beneath the head. Flags E are shown upon opposite sides of the head-like portion.

What I claim is—

The design for a rattle, substantially as 20 herein described.

In testimony whereof I affix my signature in presence of two witnesses.

JESSE A. CRANDALL.
